UNITED STATES PATENT OFFICE.

WARWICK W. WOOD, OF WINSTON, NORTH CAROLINA.

DESIGN FOR A LAYER OF TOBACCO.

SPECIFICATION forming part of Design No. 15,107, dated June 24, 1884.

Application filed July 24, 1883. Term of patent 11 years.

To all whom it may concern:

Be it known that I, WARWICK WHITEFIELD WOOD, a citizen of the United States, residing and doing business at Winston, in the county of Forsyth and State of North Carolina, have invented and produced a new and original Design for Layers of Chewing and Smoking Tobacco, of which the following is a specification, reference being had to the accompanying drawings, forming part thereof, and in which—

Figure 1 represents a plan view of a layer or disk according to my design, and Fig. 2 a central transverse sectional view of the same. Fig. 3 represents a detached view of the center piece, and Fig. 4 a detached view of one of the radial pieces.

The leading feature of my design for a layer of tobacco consists of a circular disk having a polygon center and interior lines radiating from the angles of said center to the periphery of the disk, whereby a novel and ornamental appearance is given to the said layer of tobacco, and as a consequence it will commend itself to the purchaser for this reason.

Referring more particularly to the accompanying drawings, Fig. 1 represents the de-

sign for a layer of tobacco, consisting of a series of pieces, A, side by side, with their smaller ends, c, inward around a single polygon-shaped piece, B, the several pieces A, forming the radials, being of a truncated sector shape, or arch-key form, having a curved base or larger end, a, and straight sides b and small end c, as shown in Fig. 4, and, as shown in Fig. 3, the single piece B, occupying the center, has a number of angles, d, which accord with the radiating lines b of the radials A.

Although having described and illustrated my design as applied only to a layer of chewing and smoking tobacco, yet it is apparent that the same may be applied, while having the same appearance, to layers of cakes, crackers, candies, and other similar articles.

I claim—

The design for a layer of tobacco, consisting of a circular disk having a polygon center and interior lines radiating from the angles thereof to the periphery of the disk, as shown.

WARWICK WHITEFIELD WOOD.

In presence of—

I. T. ZIGLAR.
R. D. MOSELEY.
